(57) **CLAIM**

The ornamental design for an animated image for a display screen, as shown and described.

DESCRIPTION

FIG. 1 is a first image in the sequence for an animated image for a display screen showing the new design;

FIG. 2 is the second image thereof;
FIG. 3 is the third image thereof;
FIG. 4 is the fourth image thereof;
FIG. 5 is the fifth image thereof;
FIG. 6 is the sixth image thereof;
FIG. 7 is the seventh image thereof;
FIG. 8 is the eighth image thereof;
FIG. 9 is the ninth image thereof;
FIG. 10 is the tenth image thereof;
FIG. 11 is the eleventh image thereof;
FIG. 12 is the twelfth image thereof;
FIG. 13 is the thirteenth image thereof;
FIG. 14 is the fourteenth image thereof;
FIG. 15 is the fifteenth image thereof;
FIG. 16 is the sixteenth image thereof;
FIG. 17 is the seventeenth image thereof;
FIG. 18 is the eighteenth image thereof;
FIG. 19 is the nineteenth image thereof;
FIG. 20 is the twentieth image thereof; and,
FIG. 21 is the twenty first image thereof.

The appearance of the animated image sequentially transitions between the images shown in FIGS. 1-21. The process or period in which one image transitions to another forms no part of the claimed design. The even length broken line showings of an X and a rectangle in FIGS. 19-21 form no part of the claimed design. The uneven length broken line showing of the display screen is for environmental purposes and forms no part of the claimed design.
